ROTATABLE CAR AND TRAIN-LINE COUPLER ARRANGEMENT

Robert C. Kepner and Robert A. Shields, Bloomsburg, Pa., assignors to American Car and Foundry Company, New York, N. Y., a corporation of New Jersey

Application November 18, 1947, Serial No. 786,714

6 Claims. (Cl. 213—76)

1

This invention relates to car couplers in general and in particular to couplers for use with mine or other industrial cars which are intended to be rotated about a longitudinal axis to dump the contents thereof. During recent years mines and other industrial workings have been enlarged to the point where materials must be hauled a long distance, accordingly, the trend is toward as large cars as can be worked within the limiting clearances. Also, due to the long haulage speeds have had to be increased to meet production requirements. Due to increased speeds and loads the customary hand brake has become unsafe and, accordingly, some type of power brake must be applied. With normal cars the ordinary air brake and coupling between cars can be used, however, in order to speed discharge it is preferable to rotate the cars through an angle approximating at least 180 degrees. In most instances it is found more economical to rotate the car during dumping through a full 360 degrees. It is an object, therefore, of the present invention to provide a coupling between cars so designed as to carry air or other brake actuating medium through the coupling while permitting relative rotation between cars.

A further object of the invention is the provision of an automatic coupling provided with connected piping so arranged as to permit full rotation of the coupler.

A still further object of the invention is the provision of a car coupler rotatable about a horizontal axis and carrying pipe connections so arranged as to permit passage of a brake actuating medium irrespective of the rotation of the coupler.

A yet further object of the invention is the provision of a coupler and pipe connections between cars so arranged as to permit relative rotation of the cars without uncoupling.

These and other objects of the invention will be apparent to persons skilled in the art from a study of the following description and accompanying drawings, in which

Fig. 1 is an elevational view of the couplers and pipes in connected position;

Fig. 2 is a plan view of the couplers with parts broken away to better disclose the construction;

Fig. 3 is a slightly enlarged horizontal sectional view through the one coupler element to better disclose the rotary feature of the coupler and pipe, and

Fig. 4 is a vertical sectional view taken substantially through the center of the coupler.

Referring now to the drawings in detail it will

be seen that the coupler assembly is made up of a coupler head part A adapted to receive and retain a coupler part B. The coupler parts A and B are fastened to car end sill structures C by means of channel shaped members 2. These channel shaped members are adapted to receive a rubber or other resilient buffering pad 4 located between the channel and a follower plate 6. Other rubber or resilient draft strips 8 are located forwardly of the follower plate and these are positioned between the follower plate and a retaining plate 10. Bolts 12 extend through the channel 2, follower plate 6 and front plate 10 to retain the parts in assembled relation. The channel 2 may as described be separate from the car and attached thereto in any suitable manner, or the channel 2 may be formed as a part of the car end sill if so desired. As best shown in Fig. 4, each follower plate is provided with an upstanding lug 14 against which a spring 16 may bear, which spring will counteract the overhanging weight of the coupler or coupler head and hold the same in a substantially horizontal position. Spaced arms 18 extend forwardly from each follower plate and are apertured to receive a pin 20 adapted to transmit the buff and draft forces from the coupler and coupler head to the car structure.

The coupler head A has a rigid shank extending back between spaced plates 18 for pinned connection with the pin 20. This coupler head is provided with a flat buffering face 22 surrounding an opening adapted to receive a part of the coupler. Back of the flat buffering face a latch member 24 is provided, which latch member is adapted to engage or disengage the coupler projection later to be referred to. The coupler head A can swing in a horizontal direction around its pin 20 but cannot rotate about a horizontal axis with respect to the car or any part of the coupler head assembly.

The coupler B is made up of two main parts, one of which is connected to the pin 20 and the other of which can be connected to a coupler head. These two main parts are rotated relative to each other. The outermost part of coupler B is provided with an extension 28 having a pocket 30 into which a portion of the latch 24 may drop when the coupler parts are connected. Rearwardly of the projection the coupler is provided with a flat buffering face 32 adapted to cooperate with and tightly engage the smaller buffering face 22 of the coupler head. The outer coupler part extends rearwardly of the buffering face 32 to provide what might be considered a tubular projec-

tion 34 which is adapted to surround a substantially tubular shank member 36, which is extended and provided with spaced arms 38 adapted to be connected to the pin 20 previously referred to. In order to retain the outer coupler part on the inner coupler part bolts or other means 40 are adapted to extend through portions of projection 34 and through removable collar blocks 42, which as clearly shown in Fig. 4 fit into grooves on the shank 36. Thus all buffing and draft forces received by the outer coupler part will be transmitted to the shank through the removable collars 42. In order to hold the outer coupler part against accidental rotation and in its proper position for coupling with the coupler head, a flat centering spring or other device 44 is provided which is connected at its ends to the outer coupler part and has its central part bearing on a flattened portion of shank 36.

Also, in order to retain each coupler and coupler head in a position substantially normal to the car end a heart shaped centering link 46 is inserted between the arms of the coupler elements as best shown in Figs. 3 and 4. This heart shaped centering link has a large central opening permitting its free swinging relative to the pin 20 and has spaced rearward projections 48 adapted to bear on the forward face of the follower plate 6. A projection 50 extends outwardly from the heart shaped link to bear against the back wall of a substantially cylindrical spring core member 52. The forward portion of this spring core member bears against one end of spring 54, the other end of which bears against key members 56 inserted in the forward end of the shank 36, thus any tendency for the coupler or coupler head to rotate in a horizontal plane about pin 20 will be resisted by the compression of spring 54.

In order to carry air or other brake actuating medium between cars, a flexible hose or other means 60 is connected to a short pipe 62 extending through the sides of shank 36 and through a slot 64 formed in one side of the spring core member 52. The short pipe 62 is connected to an angle 66, which in turn is connected to a pipe 68, on the forward or outer end of which is screwed a bell-like member 70. The inner surface of this bell-like member is carefully machined to fit with a small predetermined clearance over a machined projecting nipple 72. This nipple 72 is cast or otherwise formed integral with the outer member of the coupler B and is cored to provide a passage 74 extending to the side of the coupler part as best shown in Fig. 3. The outer end of this passage is internally threaded to receive half of a quick coupling device 76, the other half of which is connected to a flexible pipe or hose 78 extending to the next adjacent car. The quick coupling halves 76 are preferably of the valved type having parts so arranged that when hose 78 is uncoupled air or other brake medium can not leak out of hose 78 or out of passage 74. When, however, the quick coupling halves are brought together the brake medium may freely flow through the pipes. In order to prevent leakage of brake medium between the nipple 72 and bell-like member 70, an O-ring 80 of resilient material is inserted in a groove formed in the bell-like member 70. This O-ring sealing member will freely permit rotation between the bell-like member 70 and nipple 72 and yet effectively seal against leakage of any brake medium.

From the preceding it will be seen that the coupler B can enter the coupler head A and be

tightly locked thereto as is customary with this general type of coupling. Also, due to the fact that coupler B is made in two parts fastened together by collar blocks 42, the outer coupler part may freely rotate on the shank 36 while still transmitting buff and draft forces through the blocks 42. It will be noted that the axis of pipe 68, bell member 70 and nipple 72 coincide and also coincide with the axis of the shank portion 36 and rear projection 34. Thus any rotary motion of the outer coupler part may occur without in any way affecting the piping parts 60 to 70 inclusive. Accordingly, the cars may freely rotate about a horizontal axis relative to each other and while in a fully coupled condition without in any way disturbing the brake connections. In other words, a string of cars can be pulled through a rotary dump while standing on a grade, with the engineer having full control at all times over the brakes of the train.

In coupling cars together they can be coupled in the ordinary manner and the brake line then connected by merely pushing half of quick coupling 76 into the other half. This coupling of the halves, as previously stated, will permit free flowing of the brake fluid, thereby obviating the need for any separate valves or angle cocks so commonly used on ordinary freight cars. While the quick coupling parts 76 have been shown as projecting laterally from the coupler, it will be obvious that they can be arranged to extend longitudinally so as to quickly separate under pull in case the cars are uncoupled by merely releasing latch 24. While the invention has been described more or less in detail with specific reference to the accompanying drawings, it will be obvious that various modifications and rearrangements of parts can be made without departing from the scope of the following claims defining our invention.

What is claimed is:

1. A rotary car coupler comprising a coupler head, an inner coupler part, an outer coupler part adapted to couple with said coupler head and being rotatably mounted on said inner coupler part for rotation through more than 90 degrees about a substantially horizontal axis, a nipple member formed on the interior of said outer coupler part, a passage extending from said nipple to the exterior of said outer coupler part, and a conduit carried by said inner coupler part and rotatably sealed with respect to said nipple member to conduct a pressure medium through the inner coupler part to said nipple and passage, said rotatable seal comprising a bell-like member secured to said conduit and freely slideable over said nipple member with a predetermined clearance, and an O-ring fitted in a groove in one of said members and urged into said clearance by pressure within the conduit passage.

2. In a haulage system the combination of a pair of cars provided with cooperating coupler heads, means mounting one head on each car, at least one of said means comprising a shank connected to one car and rotatably supporting the coupler head for that car whereby said cars may while coupled rotate relative to each other through at least 90 degrees about a substantially horizontal axis, passageways carried by said shank and by said rotatably supported coupler head and being so constructed and arranged as to conduct a pressure medium past the cooperating coupler heads during relative rotation of the cars, and flexible means carried by the other car and directly connected to the last-named coupler

head to conduct a pressure medium to said passageways.

3. In a haulage system the combination of a pair of cars adapted to run on rails and provided with pressure operated brakes and cooperating coupler heads each connected to a car, at least one of the connections between the coupler head and car comprising in part a shank upon which the coupler head is mounted for rotation about a substantially horizontal axis whereby said cars may while coupled rotate through more than 90 degrees relative to each other about said axis, and conduit means carried by said cars and by said coupler head and shank and independent of the cooperating coupler head for conducting a pressure medium between the cars during rotation of the coupled cars about said axis.

4. In a haulage system the combination of a pair of cars adapted to run on rails and provided with pressure operated brakes and cooperating coupler heads each connected to a car, at least one of the connections between the coupler head and car comprising in part a shank upon which the coupler head is mounted for rotation about a substantially horizontal axis whereby said cars may while coupled rotate more than 120 degrees relative to each other about said axis, and conduit means carried by said cars and by said coupler head and shank for conducting a pressure medium between the cars during rotation of the coupled cars about said axis, said conduit means including a rotatable seal positioned substantially concentric with said axis, and also including automatically operating valved connections whereby said cars may be separated without loss of pressure medium from said conduit means.

5. In a haulage system the combination of a pair of cars adapted to run on rails and provided with pressure operated brakes and cooperating coupler heads each connected to a car, at least one of the connections between the coupler head and car comprising in part a shank upon which the coupler head is mounted for rotation about a substantially horizontal axis whereby said cars

may while coupled rotate through more than 90 degrees relative to each other about said axis, and conduit means carried by said cars and by said coupler head and shank and independent of the cooperating coupler head for conducting a pressure medium between the cars during rotation of the coupled cars about said axis, said conduit means including automatically operating separable valve connections whereby said cars may be separated without loss of pressure medium from said conduit.

6. A rotary car coupler comprising in combination, a female coupler head, a male coupler head adapted to couple with said female coupler head, 15 a shank member projecting into said male coupler head and supporting the same for relative rotation about a substantially horizontal axis, a nipple member formed on the interior of said male coupler head, a passage extending laterally outward from said nipple to the exterior of said male coupler head at one side thereof, a conduit carried by said shank member and rotatably sealed with respect to said nipple member to conduct a pressure medium through the shank to the 20 nipple and passage, and a connector carried by said male coupler head at the outer end of said passage and including a check valve normally preventing flow of pressure medium through 25 said passage.
